Inventor:

Joseph J. Adgate
per Andrew Wilson,
Attorney.

UNITED STATES PATENT OFFICE.

JOSEPH J. ADGATE, OF NEW YORK, N. Y.

WARDROBE-BED.

SPECIFICATION forming part of Letters Patent No. 340,072, dated April 20, 1886.

Application filed October 4, 1883. Renewed February 24, 1885. Serial No. 156,797. (No model.)

To all whom it may concern:

Be it known that I, JOSEPH J. ADGATE, of the city, county, and State of New York, have invented certain new and useful Improvements 5 in Wardrobe-Beds, of which the following is a specification.

My invention relates to beds in which a pivoted bed-frame is made to fold into a vertical position by means of weights applied to its inner or lower end.

In the drawings, Figure 1 is a vertical sectional view of my invention, taken on the line xz of Fig. 4, showing the bed partly folded. Fig. 2 is the same, showing the bed entirely 15 folded. Fig. 3 is the same, showing the bed entirely lowered. Fig. 4 is a vertical back view, and Fig. 5 is a vertical view, of my series of weights.

Similar letters of reference designate similar 20 parts in all the drawings.

A is the stationary case in which the other parts move.

B B are the side pieces of the bed-frame L, resting upon the rollers aa , which travel in 25 the grooves bb in the sides of the case A.

cc are rollers on the cross-piece F of the frame L.

D is the head-board, and E is a strip hinged on one side to the bottom of the head-board 30 D and on the other side to the cross-piece F. The head-board D has attached to its back the guide-block e , through which passes the rod f , which rod f is secured at both ends to the case A. By means of this feature of my invention I am enabled to reduce the friction 35 caused by the upward and downward movement of the head-board to a minimum. Grooves may be cut in the back of the head-board D, if necessary, to prevent its binding on the 40 tracks dd in its descent. This head-board D also has attached to its back the brackets or arms G G.

S S S are a series of metallic bars, which constitute the weights for operating the bed, sliding 45 upon the rod I vertically when the bed is in motion, and resting in the notches $n n n' n' n'$ in the frames H H' when the bed is closed. Each succeeding notch in the series $n' n' n'$ is 50 lower than the corresponding notch in the series $n n n$. Thus, if the notches $n' n' n'$ are respectively two, four, six, &c., inches above a horizontal line, the notches $n n n$ will be re-

spectively three, five, seven, &c., inches above the same line, or thereabout; but I do not confine myself to these proportions. The second bar from the bottom of the series S S S projects farther to the right than the first, the third projects farther to the left than the second, the fourth, again, projects farther to the right than the third, and the fifth farther to 60 the left than the fourth, and this increase of length alternately from right to left continues through the whole series. This arrangement causes one end of each succeeding bar to project beyond the end of the bar next below 65 it, so that one end of each succeeding bar will rest one notch higher than the same end of the bar immediately preceding it, and the other ends of the same two bars will rest one on the other in a single notch of the opposite frame. 70

The operation of my invention is as follows: When the bed is closed, the rollers aa are in the position shown in Fig. 2, the frame L is closely folded up into the case A, and the rollers cc are upon or near the bottom of the case 75 A. If the upper end of the frame L be then drawn forward, the frame L will swing on the rollers aa , the rollers cc will be brought against and travel up the tracks dd , approaching more nearly the bottoms of the grooves bb , pushing the frame L upward and outward, 80 and causing the rollers aa to run farther out in the grooves bb . At the same time the strip E and head-board D will be raised until the weight of the outer end of the descending frame L over- 85 balances the resistance thus caused on its inner end. At this point one of the brackets G G will engage one end of the lowest bar, S, and lift it until the bar is in a horizontal position, when it will begin to lift the lowest end of the 90 next bar, (see Figs. 1 and 4,) continuing to take up the remaining bars in the same manner as the bed descends, thus gradually increasing the weight until the bed is in the position shown in Fig. 3, when the weight of all 95 the bars S S S will be resting upon the brackets G G, and through them the head-board D and strip E upon the inner end of the frame L. As the bed-frame L descends the rollers cc will traverse tracks dd up the back of the case A, pushing the frame L gradually out 100 from the back of the case A and causing the rollers aa to travel out toward the ends of the grooves bb , thus increasing the distance be-

tween the weights S S S and the fulcrum rollers *a a*. By this means much less weight will balance the frame L than would be required if the pivots on which it turned remained all ways in a position corresponding to the position of the rollers *a a*, as shown in Fig. 2. When the bed is being folded, the weight-bars S S S will be gradually deposited in the frames H H', the rollers *a a* will slide down in the grooves *b b*, and the bed-frame will be folded closely and compactly into the case A.

By means of my invention I am enabled to adjust and increase or diminish the weight on the inner end of the frame L, so that the frame L shall open and close evenly through its whole course, and can be stopped, and will remain without being held or fastened at any desired angle.

I claim as new—

- 20 1. In a wardrobe-bed, the stationary supporting-frame A, the movable frame L, pivoted to the stationary frame A, the strip E, the head-board D, brackets G G, series of weights S S S, and supports H H', provided with the notches *n n n' n' n'*, constructed as described.
- 25 2. In a wardrobe-bed, the stationary supporting-frame A, provided with the grooves *b b* and tracks *d d*, the movable frame L, pivoted within the stationary frame A upon the rollers *a a*, and provided with the rollers *c c*,

the strip E, head-board D, brackets G G, series of weights S S S, and the supports H H' for the same, constructed as described.

3. The series of weights S S S, the guide-rod I, the stationary frame or case A, provided with the grooves *b b*, supports H H', the movable frame L, provided with the rollers *a a*, strip E, and the vertically-moving head-board D, provided with the brackets G G, all constructed substantially as described. 40

4. In a wardrobe-bed, the stationary frame A, provided with the grooves *b b* and tracks *d d*, the movable frame L, provided with the rollers *a a c c*, strip E, head-board D, guide e, and rod f, combined and operating substantially as set forth. 45

5. In a wardrobe-bed, the stationary supporting-frame provided with the grooves *b b* and tracks *d d*, the movable frame provided with the rollers *a a c c*, pivoted therein, the strip E, head-board D, and brackets G G, attached thereto, guide e, rod f, series of weights S S S, the rod I, and frames H H', for guiding and supporting said weight-bars, constructed, combined, and operating substantially as described. 50 55

JOSEPH J. ADGATE.
